UNITED STATES PATENT OFFICE

RICHARD J. SANKEY, OF LONDON, ENGLAND.

STOPPERING BOTTLES FOR AERATED OR GASEOUS LIQUIDS.

SPECIFICATION forming part of Letters Patent No. 297,298, dated April 22, 1884.

Application filed June 11, 1883. (No model.) Patented in England April 30, 1883, No. 2,176; in Germany May 26, 1883, No. 24,740; in Victoria August 7, 1883, No. 3,516; in South Australia August 13, 1883, No. 380, and in New South Wales October 11, 1883, No. 83,12,341.

To all whom it may concern:

Be it known that I, RICHARD JOHN SANKEY, a subject of the Queen of Great Britain, residing at London, England, have invented new and useful Improvements in Stoppering Bottles for Containing Aerated or Gaseous Liquids, of which the following is a specification.

This invention relates to improvements in stoppering bottles for containing aerated or gaseous liquids when such bottles are closed by internal stoppers; and the improvements consist in an improved method of fitting and fixing in the neck of the bottle the india-rubber ring which forms the seat for the stopper to bear against.

In carrying out the first part of my invention I utilize the known property of hard india-rubber, usually called "vulcanite" or "ebonite," by which such material, after having been expanded or contracted, will retain such expanded or contracted shape until it be heated, when it will recover its original shape. I employ a bottle having a shoulder or step in the neck thereof, the opening of the neck either above or below the said step or shoulder being somewhat of a conical shape, narrowing as it recedes from the shoulder or step. Over or under the shoulder or step, and resting thereon, (the stopper having been previously inserted in the bottle,) I place an india-rubber ring, such as is usually employed for use with internal stoppers. For fixing this india-rubber ring against the said shoulder or step I employ a ring of ebonite, made in the first instance of about the same size as the above-named india-rubber ring—that is to say, with a hole in the center somewhat smaller than the diameter of the stopper. I then, by means of a suitable tool, compress the outside diameter of the ebonite ring to such a size that it can be passed into the bottle, and when the ring has been placed flatwise upon the said rubber ring heat is applied in a suitable manner to the ebonite ring, and in a short time the ebonite ring will expand until it tightly fits against the surface of the neck of the bottle above or below the india-rubber ring, (as the case may be,) and will thus firmly hold the same against the hereinbefore-described step or shoulder in the bot-

tle-neck, so that it cannot be removed without first removing the ebonite ring. Instead of employing a bottle with a shoulder or step in the neck, the interior of the neck of the bottle may be formed of a suitably double-curved shape, and the shoulder or step may be constructed of one ebonite ring, and the rubber ring may be inserted and held against the step or first ring by another ebonite ring. The stopper which I find it advantageous to employ in combination with a seating constructed and fitted as hereinbefore described, consists of a hollow oval or double-cone-shaped stopper, of glass, porcelain, or other suitable sinkable material, the object of making the stopper hollow being to lighten it, so that in sinking to the bottom of the bottle when the bottle is opened the stopper shall not break or injure the bottle or be itself broken or injured. Other suitable stoppers may, however, be used with my improved seating, and the hereinbefore-described stopper may be used with the ordinary seating.

In order to enable my invention to be fully understood, I will proceed to describe the same by reference to the accompanying drawings, in which Figure 1 shows a section of the mouth of a bottle provided with a seating according to my invention; Fig. 2, a similar view, but showing the internal stopper in the position it occupies when pressed against the seating; Fig. 3, an elevation of a complete bottle; Fig. 4, a section of the bottle-neck without seating; Fig. 5, a detached plan of the india-rubber seating before being placed in the bottle; Fig. 6, plan of the vulcanite fixing-ring before compression, and Fig. 7, a plan of the same after compression; Fig. 8, a view similar to Fig. 1, but showing the vulcanite ring before being expanded against the bottle-neck; Fig. 9, section of a bottle-neck, showing the elastic seating placed under a step or shoulder in the neck; and Fig. 10, a section of a bottle-neck, showing the elastic seating fixed in position by two vulcanite rings.

Similar letters in all the figures represent similar or corresponding parts.

I will first describe my improvements by reference to Figs. 1 to 8, inclusive.

a is the bottle, and *b* the step or shoulder in

the neck thereof, the opening of the neck narrowing as it recedes from the shoulder *b*, so as to be somewhat of a conical shape.

c is the improved stopper, formed hollow and of a double-cone shape, and made of suitable sinkable material. A stopper of this construction (or any other suitable known stopper) is placed in the bottle. I then place upon the step or shoulder *b* an ordinary vulcanized india-rubber ring, *d*, such as that shown in detached plan at Fig. 5, or a ring or seating of other suitable elastic material. To fix this seating-ring in position I employ a ring of vulcanite, *e*, made in the first instance of about the diameter shown in the detached view at Fig. 6. I then compress this ring *e* by suitable means until it is reduced to such a diameter, as shown in Fig. 7, that it can be passed into the bottle *a*. The ring *e* is then laid flatwise upon the seating *d*, as shown in Fig. 8, and heat is applied to the vulcanite ring *e*, and in a short time it will expand until it tightly fits against the interior of the neck, as shown in Fig. 1, so as to firmly hold the seating *d* against the step or shoulder *b*, the conical shape of the mouth of the bottle preventing the ring *e* from rising.

The arrangement shown in Fig. 9 is substantially the same as that shown in Fig. 1, except that the seating *d* is fixed against the under side of the shoulder *b*.

Fig. 10 shows the bottle-neck formed of an oval or double-curved shape in the interior, the seating *d* being fixed between two vulcanite rings, *e' e'*, the one first inserted constituting the step or shoulder, against which the other ring holds the elastic seat.

It is obvious that various means equivalent to those above referred to may be employed for fixing the expanded ebonite or vulcanite

ring (when used as proposed by me) firmly in its seat, as required. For instance, suitable projections or recesses may be formed in the neck of the bottle, against or into which the ebonite ring or parts of it may be pressed; but the means I have hereinbefore shown seem to me to be most convenient on the whole.

Having thus described my said invention and the best means I am acquainted with for carrying the same into effect, I wish it to be understood that what I claim is—

1. The method herein described of fixing an elastic seating in the narrowing or conical neck of a bottle, consisting in first reducing in diameter a ring of hard india-rubber, usually called "vulcanite" or "ebonite," next passing it into the bottle-neck, placing it against an elastic seating in such neck, and then subjecting it to heat until the said ring expands and becomes tightly fitted in the interior of the bottle and against the elastic seating, substantially as and for the purpose set forth.

2. A bottle for internal stoppers, having a conical or narrowing opening in its neck, and having an interior rubber seating resting upon a step and held to place therein by an expanded hard-rubber ring, substantially in the manner herein shown and described.

3. A bottle for internal stoppers, having a narrowing neck, and having a seating fixed in such neck resting upon a step consisting of an expanded vulcanite ring, and held to place thereon by another expanded vulcanite ring, substantially in the manner herein shown and described.

R. J. SANKEY.
